UNITED STATES PATENT OFFICE.

EDWIN T. GREENFIELD, OF NEW YORK, N. Y., ASSIGNOR TO THE INTERIOR CONDUIT AND INSULATION COMPANY, OF SAME PLACE.

UNDERGROUND CONDUIT.

SPECIFICATION forming part of Letters Patent No. 570,168, dated October 27, 1896.

Application filed May 11, 1896. Serial No. 591,090. (No model.)

To all whom it may concern:

Be it known that I, EDWIN T. GREENFIELD, a citizen of the United States, residing at New York, in the county of New York and State of New York, have made a new and useful Improvement in Conduits, of which the following is a specification.

My invention is directed to improvements in electrical conduits, but particularly underground or subway conduits; and its objects are, first, to afford a simple and efficient means for insulating electrical conductors at manhole-crossings in systems of subways or underground conduits; second, to construct a manhole in sectional parts, so as to adapt the same for any desired number of subway or conduit tubes; third, to afford general flexibility of interconnection between the ends of subway or conduit tubes as they enter a manhole or point of distribution by the use of flexible insulating or protecting tubes. I accomplish these several objects with the means hereinafter described, the especial features of novelty of my invention being particularly pointed out in the claims at the end of this specification.

Referring now to the drawings, Figure 1 represents in part sectional and part side-elevational view a subway or conduit embracing two tiers of subway or conduit tubes and my improved form of manhole, with a flexible protecting-tubing joining one of said conduit-tubes to a branch leader or circuit located above ground. Fig. 2 represents in plan view a subway or conduit embracing a number of subway or conduit tubes entering a manhole and provided with my improved means of effecting flexible interconnecting protecting means for uniting any pair of such subway or conduit tubes, the top of the manhole and the cover of the subway being removed for the purpose of illustrating the interior structure of said parts. Fig. 3 is a transverse section taken on the line $\alpha\alpha$, Fig. 1, and as seen looking from right to left in the direction of the arrows upon that figure of the drawings. Fig. 4 is a plan view of the manhole as seen looking at Fig. 3 from the top toward the bottom of the drawings.

Referring now to the drawings in detail, and first to Figs. 1 to 4, inclusive, D repre-

sents a wooden trough, preferably creosoted or treated in any of the well-known ways to protect it from the action of water, and D' a wooden cover therefor.

P' P' P' are rows or tiers of subway or conduit tubes made, preferably, of paper treated or cured in the usual way with insulating material, said tubes being properly spaced and sustained by wooden spacing-strips when they are laid in the conduit-trough D and afterward surrounded with molten asphalt or pitch, which is allowed to harden, after which the cover D' is secured in place.

M represents the top or upper portion of a manhole, made, preferably, of cast-iron and of rectangular form, said top portion being strengthened by radially-disposed ribs R² R², &c., and T is a removable cover therefor. The lower surface of this top portion of the manhole is provided with a rim, flange, or extension K', which is adapted to fit snugly over the rectangular portion O of the body of the manhole, which rectangular portion is provided with a similar flange at its lower surface adapted to fit in a like manner over a corresponding flange upon another sectional part O'. The bottom sides of the top portion M and the corresponding top and bottom sides of the portion O are provided with semi-circular openings F F, which, when the parts are placed one upon the other, after the manner shown in Fig. 3, constitute the inlets for the conduit or subway tubes P' P'. By thus constructing the manhole of sectional parts O O', I am enabled to build up a manhole to any desired height, so as to accommodate any number of subway or conduit tubes, this feature of flexibility of a manhole being deemed by me as important, in that it adapts the invention for ready use in accordance with the demands of the system where used. The lower or bottom section of the manhole O' is provided with an outlet J for drainage. In the top portion of the manhole I provide an opening through a projecting portion L for the purpose of enabling one to convey a branch feeder or main from the subway to a point above ground, as an electric-light post or any other service usage. When the manhole is placed in position between the adjacent ends of the subway, so that the open-

ings F F are in alinement with the incoming subway or conduit tubes P' P' P' P', as shown in Figs. 1 and 2, I insert short metallic sleeves P P through the openings F F and around the incoming subway or conduit tubes, said sleeves being provided with screw-threads on their inner ends. I then provide a temporary dam around said screw-threaded sleeves at the openings and pour liquid asphalt at 5 the conduit-box D around the free ends of the pipes P' and the adjacent ends of the metallic sleeves P until the spaces around the tubes and sleeves are completely filled with said asphalt, thereby making an absolutely water-tight joint between the manhole, the conduit-boxes, and the contained tubes and sleeves.

R R represent expansible soft-rubber tubing of sufficient length, when expanded, to afford cross connection between any pair of subway or conduit tubes located within the manhole. These tubes R R are secured by wire wrappings w w at their opposite ends to T-shaped hard-rubber thimbles t t. 20 N N are swivellocking-nuts screw-threaded on their inner surfaces and each provided with a shoulder having a bearing against the T-shaped portion of its thimble t, as clearly shown in Figs. 1 and 2. 25 When it is desired to cross-connect any pair of subway or conduit tubes P' P', the conductor is drawn therethrough to the manhole and one of the flexible interconnecting tubes R R is secured to the inner end of said subway-tube in the manner shown in folded position near the center of Fig. 2. The conductor is drawn forward to the other conduit-tube through which it is to be conveyed and the swivel-nut N is connected to the screw-thread upon the sleeve which surrounds said subway tube or conduit, thereby expanding the soft-rubber tube in the manner shown in the bottom portion of the drawings in Fig. 2.

In Figs. 1 and 3 I have illustrated a means 45 of connecting one of the subway-tubes with a lamp-post or other point of service above-ground and surrounding the conductor running thereto by one of my improved flexible insulating-tubes, R' representing such tube 50 and being provided at its opposite ends with insulating-thimbles t t and locking-nuts N', one of which is secured to the upper portion of a locking-thimble K, provided with insulating-linings P² P³, the outer end of said flexible tubing being connected by the swivel-nut N to the end of a tube which is secured 55 to the manhole by two nuts Q Q, as clearly shown in Fig. 3. With such an arrangement of flexible tubing I am enabled to furnish 60 cross connections between any two of a series of subway-tubes and to afford quick and easy access to the conductor or conductors surrounded thereby. I am also enabled to in a similar manner insulate with one of my 65 improved flexible cross-connectors any conductor which runs to a point aboveground.

I am aware that it is broadly old to cross-

connect subway-tubes in manholes by rigid telescoping sleeves, and I make no claim hereinafter broad enough to include such a structure, my broadest claim in relation to such cross connections being the feature of flexible cross-connecting tubes which permit of any interconnection desired. 70

Having thus described my invention, what I claim, and desire to secure by Letters Patent of the United States, is—

1. In a subway or conduit a series of conduit-tubes extending into a manhole or to a point of distribution, each of said conduit-tubes being provided with screw-threaded ends and corresponding screw-threaded locking-nuts attached to short sections of insulating-tubing for cross-connecting said tubes, substantially as described. 80

2. In a subway or conduit a series of conduit-tubes extending into a manhole or to a point of distribution, in combination with expansible cross-connecting tubes and means for securing said expansible tubes to any pair 90 of said conduit-tubes, whereby the insulating continuity of said tubes is effected, substantially as described.

3. A pair of conduit-tubes having their ends located in close proximity to each other, 95 in combination with an expansible insulating connecting-tube provided with means for uniting the opposite ends thereof to said conduit-tubes, substantially as described.

4. In a subway or conduit a series of conduit-tubes extending into a manhole from opposite sides, in combination with a series of expansible cross-connecting tubes provided with means for connecting said expansible tubes to the ends of the oppositely-located 105 conduit-tubes, substantially as described.

5. A subway or conduit provided with expansible means for joining two or more conduit-tubes and an expansible side or branch tube running therefrom to a service conduit-tube located aboveground, substantially as 110 described.

6. In a subway a series of conduit-tubes extending into a manhole, in combination with a series of expansible cross-connecting 115 tubes adapted to connect said conduit-tubes together in pairs and expansible branch connecting-tubes, one or more, for connecting said conduit-tubes to lateral or side branches, substantially as described.

7. In a subway system a series of conduit-tubes extending into a manhole; a series of expansible cross-connecting tubes for cross-connecting said conduit-tubes together in pairs, in combination with detachable means 125 for securing said cross-connecting tubes to the ends of the tubes, substantially as described.

8. A subway consisting of a series of conduit-tubes located in a conduit-tube trough, 130 the ends of said tubes extending into a manhole and being surrounded each by a short metallic sleeve and all embedded in asphalt which binds the tubes, the sleeves, the con-

duit-trough and the manhole firmly together, substantially as described.

9. A manhole consisting of a number of sections of substantially rectangular shape provided each with a rim, flange or extension and having lateral or side openings between said sections for receiving the ends of conduit-tubes whereby said sections may be placed the one upon another and thereby adapted to vary the number of conduit-tubes in proportion to the requirements, substantially as described.

10. A manhole constructed of a number of sectional parts provided each with a rim,

flange or extension and semicircular openings in the opposite edges of the parts, the arrangement being such that when the separate sections of said manhole are placed the one upon the other the opposite semicircular parts constitute openings for the admission of conduit-tubes, substantially as described.

In testimony whereof I have hereunto subscribed my name this 8th day of May, 1896.

EDWIN T. GREENFIELD.
